UNITED STATES PATENT OFFICE.

MAURICE MATHY OF LIÈGE, BELGIUM.

VISE FOR HOLDING GLASSES, &c.

1,369,454.

Specification of Letters Patent. Patented Feb. 22, 1921.

Application filed June 26, 1919. Serial No. 307,034.

To all whom it may concern:

Be it known that I, MAURICE MATHY, manufacturer, a subject of the King of Belgium, and resident of Liège, in the Kingdom of Belgium, have invented certain new and useful Improvements in and Relating to Vises for Holding Glasses, &c.; and I do hereby declare the following to be a full, clear and exact description of the invention, 10 such as will enable others skilled in the art to which it appertains to make and use the same, reference being had to the accompanying drawing, and to letters or figures of reference marked therein, which form a part 15 of this specification.

This invention relates to vises adapted for holding glasses and so forth while being cut or otherwise operated upon and which exert the necessary holding pressure upon 20 the glass by means of two sets of arms operated simultaneously. One of the sets of arms acts upon the foot of the glass so as to press it against a supporting plate, while the other set of arms acts upon the upper 25 part of the glass.

The vise forming the subject of this invention differs from vises of the same type by its simplified construction and operation.

According to the present invention the 30 vise comprises a sleeve slidably mounted on a stationary column, carrying an adjustable supporting plate, and by its movement operating the said sets of arms; one set of arms is pivotally mounted on the supporting 35 plate and is capable of adjustment relatively to the stationary column, and the other set of arms is pivotally mounted on this column. The positions of the joints of connection to the sleeve of the connecting 40 rods for operating the different arms may be adjusted also. All these adjustments can be effected by means of set screws.

In the accompanying drawing is shown, by way of example, one form of construction according to this invention, Figure 1 being a perspective view of the complete invention, and Fig. 2 a fragmental vertical section illustrating the mounting of the sliding sleeve.

50 In the interior of a stationary column 1 is slidably mounted a shaft 23 carrying the supporting plate 2. This shaft may be held in any desired position by means of a set screw 3.

55 On the supporting plate 2 are pivoted at 4 three arms 5 adapted to press the foot of the glass against the plate 2.

Three additional arms 7, adapted to hold the upper part of the glass, are pivoted at 8 to small columns 9 supported in brackets 60 10 projecting from the column 1.

The arms 5 are operated by connecting rods 11 hinged at 12 to a sleeve 13 sliding on the column 1 and actuated by a lever 14 pivoted at 15 to the base 16 of the apparatus.

The arms 7 are actuated by the same lever by connecting rods 17 hinged at 18 to the said sleeve.

For the purpose of adjusting the connecting rods 11 and 17 on the sleeve 13, the hinges 12 and 18 are not formed on the sleeve itself but on rings 19 and 20 which can be adjusted in any required position on the sleeve 13 by means of set screws 21 75 and 22.

The apparatus is also provided with a pad 6 of resilient material, for example of leather or felt, which is placed between the foot of the glass and the supporting plate 80 2. The ends of the arms 5 and 7 which come into contact with the glass are also provided with suitable devices (rollers or pads of leather) so as to obtain a resilient contact between the arms and the glass. 85

It will be easily understood that by adjusting the shaft carrying the supporting plate 2 in the column 1 and by adjusting the rings 19 and 20 on the sleeve 13, the apparatus can be adjusted so as to grip any 90 size or type of glass.

What I claim is:

A vise for holding glasses and so forth comprising in combination a stationary column, a shaft adjustable in said column and carrying a supporting plate, a sleeve adapted to slide on said column, rings adjustably mounted on said sleeve, two sets of arms, one set pivotally mounted on the said column and the other set pivotally mounted on 100 the supporting plate, said arms being adapted to hold the glass, connecting rods attached to the arms and hinged to the rings, and mechanism for operating the sleeve so as to bring the arms simultaneously into position for holding the glass. 105

In testimony whereof I affix my signature in presence of two witnesses.

MAURICE MATHY.

Witnesses:

LEONARD LEVER,
GEORGES VANDER HALGHEN.
